Specification for Design.

Patented Feb. 4, 1919.

Application filed May 4, 1918. Serial No. 232,649. Term of patent 14 years.

To all whom it may concern:

Be it known that we, CECIL R. HUBBARD, a subject of the King of Great Britain, residing at Baden, Beaver county, Pennsylvania, and HOMER G. KNODERER, a citizen of the United States, residing at Edgeworth, county of Allegheny, and State of Pennsylvania, have invented a new, original, and ornamental Design for a T-Base for Fittings for Electrical-Conductor Conduits, of which the following is a specification, reference being had to the accompanying drawing, forming a part thereof.

Figures 1, 2 and 3 are, respectively, top plan view, bottom plan view and side elevation of a T-base for fittings for electrical conductor conduits.

We claim:

The ornamental design for a T-base for fittings for electrical conductor conduits, as shown.

CECIL R. HUBBARD.
HOMER G. KNODERER.
